SKATE SHARPENER

Edwin Francis Ives, Wallingford, Conn.

Application July 21, 1947, Serial No. 762,421

10 Claims. (Cl. 51—102)

1

The present invention relates in general to skate-sharpening devices and more especially to a mobile-unit adapted to sharpen ice skates without removing them from the skater's feet.

An object of the invention is to provide a superior ice-skate sharpening-device which may be readily transported to the edge of an ice-skating rink or frozen pond and used by the skaters to sharpen their own skates while the latter are still on their feet.

A further object of the invention is to provide a superior mobile skate-sharpening device which is durable, inexpensive to manufacture, simple to operate and which is designed to sharpen skates accurately to individual requirements.

With the above and other objects in view as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a perspective view of the mobile skate-sharpening unit of this invention shown in conjunction with transporting-means;

Fig. 2 is an enlarged horizontal sectional view of the mobile skate-sharpening unit shown in Fig. 1 with the platform of the unit removed.

Fig. 3 is an end elevation of the unit shown in Fig. 2 on section line 3—3 thereof;

Fig. 4 is an end elevation of the unit of Fig. 2 on section line 4—4 thereof showing by means of broken lines a skate-blade mounted in the blade-supporting means of the device;

Fig. 5 is an enlarged broken plan view of the platform of the unit showing details of the skate-blade guide-means, part of which is broken away to show the guard-plates and the latch-means therefor;

Fig. 6 is an end elevation in section of the skate-blade guide-means including the guard-plates therefor on section line 6—6 of Fig. 5;

Fig. 7 is an end elevation in section on line 7—7 of Fig. 5 showing details of the latch-means of the guard-plates; and

Fig. 8 is a perspective view of one of the blade-gripping fingers, detached.

In carrying out the present invention, a mobile skate-sharpening unit is provided which is indicated generally at 10 in Fig. 1 and comprises, in brief, a box-like base-member 11 provided with a platform 12 and a pair of insulation-covered handrails or hand-holds 13, the unit being

2

grounded as at 480 to a steel-edged runner of the transporting-means, hereinafter described.

When the mobile skate-sharpening unit 10 is in use, it is preferable to mount the latter on a support which, in the present embodiment, comprises transporting-means 14. The latter is made in the form of a sled consisting of spaced parallel steel-edged runners 15 and a platform secured to the top edges of the runners. As shown in the drawings, the platform consists of a plurality of spaced parallel boards 16 extending transversely of the runners, the boards being widely spaced apart adjacent the rear end of the platform to provide two relatively-widely-spaced parallel recesses 17. Secured to the underside of the base-member 11, as indicated in Fig. 3, and extending transversely from opposite sides thereof, is a pair of spaced parallel feet 19 which are adapted to engage in the corresponding recesses 17 of the platform thereby to firmly but demountably secure the mobile-unit on the platform of the transporting-means. Although the sled 14 shown herein is highly satisfactory, it will be understood that the mobile-unit 10 may be mounted on any other suitable type of transporting-means, either as an integral or separate unit thereof. Moreover, it should be pointed out that the transporting-means 14 of this invention is designed to function as a crate for shipping the mobile-unit 10, the lateral spacing of the runners 15 of the sled being such that the mobile-unit may be nested therebetween. To this end, the handrails or hand-holds 13 are adapted to be demountably secured to the mobile-unit so as to be readily removed therefrom and packed with the sled and mobile-unit for shipping.

Referring more particularly to Figs. 2, 3 and 4, the mobile-unit 10 of the skate-sharpening device comprises the box-like base-member 11 consisting of a bottom 20, to the underside of which the feet 19 are secured; spaced parallel substantially-vertical side panels 21, each provided with a screened aperture 22 for the purpose herein-after described; and substantially-vertical front 45 and rear panels 23, the latter being fastened by hinges 24 to one of the side panels 21 so as to swing outwardly with respect to the bottom 20 and side panels 21 of the base-member 11. The latter is preferably wood, whereas the side panels 50 and end panels are preferably sheet metal, although any other materials or combinations of materials may be used. To assist in opening the end panels, 23, the latter are provided with handles 25.

55 The top of the base-member 11 comprises the

aforesaid platform 12 which is preferably wood and substantially equal in width to the width of the box-like base-member 11, the length of the platform 12 being, however, greater than the length of the base-member 11 so as to provide overhanging end-portions 27 each having apertures 28 adjacent the front and back edges thereof respectively, to accommodate the upper ends of a pair of stanchions 29. The latter constitute supporting-means for the detachable hand-holds 13 and to this end, comprise tubular-members secured at their lower ends to the outer ends of the feet 19 of the base-member, the respective upper ends of the stanchions 29 being arranged to project up through the aforesaid apertures 28 of the platform. Secured on the upper ends of the stanchions above the platform 12, are suitable coupling-sleeves 30 by which the lower ends of the respective hand-holds 13 are adapted to be detachably secured thereto.

Assembled within the box-like base-member 11 is the skate-blade sharpening-means comprising an abrasive wheel 31 secured to the outer free end of a spindle 32 which is rotatably mounted in a sleeve 33 secured to or formed as an integral part of an oscillatable arm 34. The latter extends from front to back of the box-like base-member 11 parallel to and substantially intermediate the vertical side panels 21 thereof, the longitudinal axis of the sleeve 33 extending substantially at right angles to the arm. The rear end of the arm 34 is pivotally mounted by a pivot pin 35 in a bearing-block 36 secured to the bottom 20 of the base-member, as indicated clearly in Figs. 2 and 3. The forward or outer free end 37 of the oscillatable arm 34 extends forwardly of the transverse sleeve 33 and is bifurcated to provide a vertical slot 38, the spaced parallel sides of which are adapted to engage closely on opposite sides respectively of a vertical guide-rod 39, the upper and lower ends of which are fixedly secured to the platform 12 and bottom 20 respectively of the base-member.

The outer free end 37 of the oscillatable arm 34 is adapted to be supported by yieldable-means, and to this end a collet 40 is fixedly secured on the lower end of the guide-rod 39 and provided with an annular shoulder constituting a seat for the lower end of a coil-spring 41, the upper end of which is arranged to thrust against the underside of a washer 42 mounted on the guide-rod and held by the force of the spring against the underside of the outer forked end 37 of the oscillatable arm. Bearing against the top of the forked end 37 of the arm and threadedly mounted on the guide-rod between the former and the underside of the platform 12, is an adjustable tension-regulating nut 43. The latter constitutes an adjustable stop for resisting upward movement of the outer free end 37 of the arm due to the upwardly-directed thrust of the coil-spring 41. In the same respect, by turning down the adjusting-nut 43 on the threaded end of the guide-rod, the nut 43 also constitutes means for positively lowering the outer free end 37 of the oscillatable arm so as to effect a proper adjustment of the abrasive wheel 31 with respect to the platform 12, as hereinafter described.

Mounted on the opposite end of the spindle 32 is an exhaust fan 44 which is adapted to lie immediately opposite the screened aperture 22 of the adjacent side panel 21. When this exhaust fan 44 is rotated, it is adapted to remove dust and other light particles from the interior of the box-like base-member 11.

The abrasive wheel 31 and exhaust fan 44 are adapted to be driven by means of a pulley 45 which is secured to the spindle between the abrasive wheel and the corresponding end of the sleeve 33 and connected by a V-belt 46 to the drive-pulley 47 of a power source. In the present embodiment, the latter comprises an electric motor 48, but it will be appreciated that other forms of power-supply means may be utilized.

10 The direction of rotation of the pulley-belt drive-means of the abrasive wheel is away from the operator as the latter faces the front of the mobile-unit, as indicated by the arrow in Fig. 2, as a consequence of which the oscillatable arm 34 has a tendency to lift up and hence to be resiliently held by the force of the coil-spring 43.

15 It is also within the purview of the invention to include a dressing-tool for truing up the periphery of the abrasive wheel. To this end, an inverted substantially-U-shaped bracket 49 is secured to the bottom 20 of the base-member 11 in the vertical plane of the periphery of the abrasive wheel. The bracket 49 is provided on 20 its underside with an adjusting-screw 50 which extends longitudinally thereof and has a knurled head 51 at its forward end for turning the screw in the bracket.

25 Mounted on the screw 50 is a nut 52 having

30 an upwardly-projecting post 53 adapted to engage in a longitudinal slot in the top of the bracket. The post 53 constitutes pivotal supporting-means for the disk-shaped base 54 of a bifurcated bracket 55 which is formed integrally 35 with the disk-shaped base 54 and substantially perpendicular thereto. Pivoted supported in the substantially-vertical slot of the forked bracket 55 by a pin 56 is a pivot-block 57. The latter is provided with a transverse aperture 58 40 in its upper end substantially at right angles to the pivot pin 56 to receive a connecting-pin 59 for mounting a yoke-member 60 to the pivot-block for pivotal movement in a vertical plane at substantially right angles to the vertical plane of the 45 pivot-block, the yoke-member 60 having a dressing wheel 61 mounted on the upper end thereof. The dressing wheel 61 is adapted thus to be moved longitudinally to and from the periphery of the abrasive wheel, and to be swung around to the right or left-hand sides respectively of the abrasive wheel by pivoting the base-member 54 about the post 53. Moreover, the dressing wheel 61 may be swung to and fro about the pivot pin 56 in the vertical plane of the periphery of the 50 abrasive wheel, or in a vertical plane at right angles thereto, as explained above, suitable indices and clamping-nuts being provided, as shown in Fig. 4, for securing the dressing wheel in any of its adjusted positions.

55 During the grinding operation some relatively heavy particles of metal may be formed and to remove these from the base-member, it is proposed to mount a channel-shaped shield 62 therein immediately to the rear of the periphery of the grinding wheel. The shield is suitably supported substantially vertically between the bottom 20 of the base-member and the platform 12 thereof, the lower end of the shield being opposite a vertical aperture 63 in the bottom 20 of the base-member. Thus, heavy particles may be deflected by the shield through the aperture 63 onto the ground or floor beneath the base-member.

60 Referring more especially to Figs. 5, 6 and 7, the platform 12 of the box-like base-member 11

is provided with an aperture or slot 64 to receive an upper peripheral portion of the abrasive wheel, the extent to which the periphery of the abrasive wheel projects up into the slot 64 being controlled by the aforesaid adjusting-nut 43. 5 The slot 64 is coextensive with the longitudinal center-line of a recess 65 of substantially-rectangular cross section formed in the top of the platform 12 and extending from front to rear thereof. The recess 65 is adapted to accommodate the 10 skate-blade guide-means and the guard-plates thereof.

The skate-blade guide-means are indicated generally at 66 and comprise two flat strips of 15 relatively-stiff steel or other suitable material substantially rectangular in cross section and equal in length to the length of the recess 65. These flat metal strips, hereinafter referred to as rails, are adapted to extend longitudinally of the recess 65 and to be supported on edge therein, the pair of rails being held in spaced parallel relationship by a plurality of rollers 67 pivotally mounted therebetween. One roller 67 is mounted at each end respectively of the pair of rails 66 and two other rollers 67 are mounted substantially equidistantly between the rearmost roller and the rear end of the slot 64, as indicated clearly in Fig. 4.

The pair of rails 66 and the four rollers 67 constitute a unit assembly adapted to be supported in the recess 65 in longitudinal alignment with and directly over the slot 64 thereof. To this end, a pair of upstanding spaced parallel brackets 68 are mounted on the bottom 69 of the recess 65 at opposite ends thereof respectively for supporting the corresponding ends of the rail assembly. The fastening-means for securing the opposite ends of the rail assembly to the brackets 68 may be rivets or a similar type of securing-means, although it is preferable that one end of the rail assembly be detachably secured to its respective brackets by removable fastening-means so as to enable the rail assembly to be swung up about its opposite end out of the recess 65 of the platform and hence facilitate adjustment and cleaning of the skate-blade sharpening-unit. Cooperatively associated with the rail assembly is a pair of skate-blade gripping-means 70 which constitute resilient relatively-stiff sheet-metal fingers, each finger being secured at one end to one of the rails flat against the vertical outside wall thereof and at a point thereon immediately to the rear of the rear end of the slot 64. Moreover, each finger 70 is adapted to extend forwardly longitudinally of the rails and is provided on its upper edge with a right-angle flange 71 adapted to extend inwardly over the upper edge of the corresponding rail, each flange having a beveled leading edge 72 and a straight edge 73 forwardly thereof. When the fingers 70 are mounted on the respective rails, the beveled leading edges 72 cooperate to form a converging slot to guide the skate-blade into the slot formed by the cooperation of the spaced parallel straight edges 73 of the fingers. The distance between the latter is normally slightly less than the average width of a skate-blade so that when a skate-blade is drawn between the spaced parallel straight edges 73, the latter will be spread apart slightly, the inherent resistance of the relatively-stiff fingers acting to grip the skate-blade firmly therebetween. As shown clearly in Figs. 5 and 6, the spaced parallel straight edges 73 of the fingers 70 are disposed substantially intermediate the opposite ends of the slot 64 in the top of the

platform and immediately above the highest portion of the abrasive wheel and hence grip the skate-blade at that portion thereof which is in engagement with the abrasive wheel during the grinding operation.

The skate-blade guide-means including the skate-blade gripping-means are adapted to be shielded by a pair of guard-plates. The latter are indicated at 74 each comprising an elongated flat sheet-steel member, the width of which is slightly less than one-half the width of the recess 65. The outer longitudinal edge of each plate is hinged at its opposite ends respectively, as at 75, to adjacent edges of the recess so that the plate may swing upwardly and outwardly therefrom, while the inner edge of each guard-plate is adapted to be supported in substantially the horizontal plane of the top of the platform 12 by means of a longitudinal vertically-depend- 15 ing flange 76 provided on the underside of the guard-plate adjacent to but set back from its inner edge, the lower edge of each flange 76 being adapted to engage on the bottom 69 of the recess 65. As shown clearly in Fig. 6, the spaced-par- 20 allel longitudinal inner edges of the guard-plates, in the normal position thereof, overlie the corresponding upper edges of the rail assembly and cooperate to form a longitudinal slot the width of which is only slightly greater than the width of a skate blade. Thus, the guard-plates prevent inadvertent damage to the skate-blade 25 guide-rails and gripping-fingers.

Since it is desirable to lock the guard-plates 74 in operative position, each respective flange 76 thereof is provided with a pair of transverse slots 77 formed at longitudinally-spaced points thereon as indicated in Fig. 5, each slot being adapted to receive the outer free end of a latch-member 78. Each latch-member comprises a relatively- 30 short stiff piece of sheet metal pivoted at its rear end to one end of a draw-plate 79, two of 35 which are provided in the present embodiment, each being mounted on the bottom 69 of the recess 65 on opposite sides respectively of the 40 guide-rails 66, and more particularly in the re- 45 spective longitudinal channels formed between the vertical flanges 76 of the corresponding 50 guard-plates 74 and the opposite substantially- 55 vertical walls of the recess 65. Each draw-plate 60 comprises an elongated substantially-flat stiff 65 piece of sheet metal provided adjacent its op- 70 posite ends respectively with longitudinally-ex- 75 tending arcuate cam-slots 80 through each of 80 which projects a substantially-vertical guide-pin 81. The lower end of each guide-pin is fixedly 85 secured in the bottom 69 of the recess 65, while 90 the upper end of each guide-pin is provided with 95 a flanged head 82 (see Fig. 7) adapted to engage 100 in an aperture 83 formed in the latch-member 78 105 of the corresponding end of the draw-plate. Re- 110 ferring to Fig. 5, the aperture 83 of each respec- 115 tive latch-member 78 is intermediate its pivot- 120 pin and its outer free end and hence it will be 125 clear that as each draw-plate is moved longi- 130 tudinally in its respective channel, the displace- 135 ment of each cam-slot relative to the fixed guide- 140 pins of the latches oscillates the latter so as to 145 advance or retract the free ends thereof into 150 and from the respective slots 77 of the guard- 155 plate flanges 76, depending upon the direction 160 of movement of the draw-plates. The simulta- 165 neous longitudinal movement of the latter is ef- 170 fected by means of a resilient bail or handle 84 175 secured to the rear ends of the draw-plates, the 180 longitudinal movement thereof being accom-

panied by the simultaneous inward and outward movements of the respective draw-plates due to the coaction of their arcuate cam-slots 80 with the fixed guide-pins 81. Moreover, since the resilient force of each arm of the bail 84 is directed outwardly, the draw-plates are normally resiliently held thereby in their outwardly-spread-apart position and resist being drawn inwardly to move the high point of their cam-slots past the fixed guide-pins. Hence, the draw-plates are resiliently held at either extreme of their longitudinal transverse movement and resist inadvertent displacement therefrom.

In operating the mobile skate-sharpening unit, the motor 48 is connected to a suitable power supply, whereupon the abrasive wheel and exhaust fan are rotated. The skater then mounts the lower platform and inserts the blade of his skate, the latter being still on his foot, between the spaced-parallel edges of the guard-plates 74 of the upper platform 12 with the skate-blade resting on the rollers 67 at the far end of the platform. The skater then draws his skate forwardly through the slot presented by the spaced-parallel edges of the guard-plates and into the leading edges of the skate-blade gripping-fingers 70. As the skate-blade enters the spaced-parallel straight edges 73 of the gripping-fingers, the blade is gripped and supported firmly thereby, while its lower edge is engaged by the upper periphery of the abrasive wheel, which makes a longitudinal grinding cut on the bottom edge of the blade, the grinding cut beginning at the rear end of the blade and moving to the front end thereof as the skater draws his skate from the far end of the platform to the front end thereof. During the grinding operation, the heavier particles of metal are conveyed out of the base-member by the channel-shaped shield 62, which directs the heavier particles out through the aperture 63 in the bottom thereof. Any dust or other light particles which are formed by the grinding operation are drawn out of the box by means of the exhaust fan described above.

Since the oscillatable arm 34 is adapted to yield to pressure applied on the periphery of the abrasive wheel, there is no possibility of the latter gouging or forming an unusually deep cut in the skate-blade. It should be pointed out, moreover, that by adjusting the elevation of the abrasive wheel by means of the adjusting-nut 43, a heavy or light cut may be formed in the skate-blade and that under all circumstances the cut will be uniform, due to the constant force applied by the coil-spring 41 to the outer free end of the oscillating arm 34.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A mobile skate-sharpening device comprising: a base-member provided with a platform having a longitudinal aperture therein; skate-blade guide-means comprising a pair of spaced-parallel guide-rails secured to the top of said platform parallel to and along opposite edges respectively of said longitudinal aperture, and members permanently mounted between said

guide-rails and spaced longitudinally thereof to support a skate-blade symmetrically of the longitudinal axis of said aperture; hand-holds fixed to said platform; an abrasive wheel mounted on said base-member beneath said platform with a peripheral portion of said abrasive wheel arranged normally to project up into said aperture between said skate-blade guide-means and symmetrical with respect to the longitudinal axis of said aperture; and power-means mounted on said base-member constructed and arranged to drive said abrasive wheel.

2. In a mobile skate-sharpening device, the combination including: a base-member provided with a platform having a longitudinal slot therein; skate-blade guide-means comprising a pair of spaced-parallel guide-rails secured to the top of said platform parallel to and along opposite edges respectively of said longitudinal slot; hand-rails fixed to said platform; an abrasive wheel; means to mount said abrasive wheel on said base-member comprising an oscillatable arm and a yieldable member cooperatively associated with said oscillatable arm normally to hold a peripheral portion of said abrasive wheel up in the said longitudinal slot between said skate-blade guide-means; and power-means mounted on said base-member constructed and arranged to drive said abrasive wheel.

3. In a mobile skate-sharpening device, the combination including: a base-member provided with a platform having a longitudinal slot therein; skate-blade guide-means comprising a pair of spaced-parallel guide-rails secured to the top of said platform parallel to and along opposite edges respectively of said longitudinal slot; handrails fixed to said platform; an abrasive wheel; means to mount said abrasive wheel on said base-member comprising an oscillatable arm and a yieldable member cooperatively associated with said oscillatable arm normally to hold a peripheral portion of said abrasive wheel up in the said longitudinal slot between said skate-blade guide-means; power-means mounted on said base-member constructed and arranged to drive said abrasive wheel; and adjusting-means cooperatively associated with said oscillatable arm and said yieldable member to limit the movement of said abrasive wheel up into the said longitudinal slot.

4. A mobile skate-sharpening device comprising: a base-member provided with a platform having a longitudinal slot therein; skate-blade guide-means comprising spaced-parallel rails secured to the top of said platform along opposite edges respectively of said slot, skate-blade supporting-rollers mounted between said rails at longitudinally-spaced points therealong to support a skate-blade symmetrically of the longitudinal axis of said slot, and resilient skate-blade gripping-fingers secured to said guide-rails intermediate said rollers; handrails fixed to said platform; an abrasive wheel mounted on said base-member beneath said platform with a peripheral portion of said abrasive wheel arranged normally to project up into said slot between the spaced-parallel rails of said guide-means and symmetrical with respect to the longitudinal axis of said slot; and power-means mounted on said base-member constructed and arranged to drive said abrasive wheel.

5. A mobile skate-sharpening device comprising: a base-member provided with a platform having a longitudinal slot therein; skate-blade

guide-means comprising spaced-parallel rails secured to the top of said platform along opposite edges respectively of said slot, skate-blade supporting-rollers mounted between said rails at longitudinally-spaced points therealong, and resilient skate-blade gripping-fingers secured to said guide-rails intermediate said rollers; handrails fixed to said platform; an abrasive wheel mounted on said base-member beneath said platform with a peripheral portion of said abrasive wheel arranged normally to project up into said slot between the spaced-parallel rails of said guide-means; power-means mounted on said base-member constructed and arranged to drive said abrasive wheel; and longitudinal guard-plates hinged to the top of said platform in spaced-parallel relationship and on opposite sides respectively of said longitudinal slot, said guard-plates being arranged normally to overlie the upper edges of said guide-rails and said resilient skate-blade gripping-fingers.

6. A mobile skate-sharpening device comprising: a base-member provided with a platform having a longitudinal slot therein; skate-blade guide-means comprising spaced-parallel rails secured to the top of said platform along opposite edges respectively of said slot, skate-blade supporting-rollers mounted between said rails at longitudinally-spaced points therealong, and resilient skate-blade gripping-fingers secured to said guide-rails intermediate said rollers; handrails fixed to said platform; an abrasive wheel mounted on said base-member beneath said platform with a peripheral portion of said abrasive wheel arranged normally to project up into said slot between the spaced-parallel rails of said guide-means; power-means mounted on said base-member constructed and arranged to drive said abrasive wheel; longitudinal guard-plates hinged to the top of said platform in spaced-parallel relationship and on opposite sides respectively of said longitudinal slot, said guard-plates being arranged normally to overlie the upper edges of said guide-rails and said resilient skate-blade gripping-fingers; and latch-means constructed and arranged to lock and unlock said guard-plates to and from the top of said platform.

7. In a mobile skate-sharpening device, the combination including: a base-member provided with a platform having a longitudinal slot therein; skate-blade guide-means comprising spaced-parallel rails secured to the top of said platform along opposite edges respectively of said slot, skate-blade supporting-rollers mounted between said rails at longitudinally-spaced points therealong to support a skate-blade symmetrically of the longitudinal axis of said slot and resilient skate-blade gripping-fingers secured to said guide-rails intermediate said rollers; handrails fixed to said platform; an abrasive wheel; means to mount said abrasive wheel on said base-member comprising an oscillatable arm and a yieldable member cooperatively associated with said arm normally to hold a peripheral portion of said abrasive wheel up in said longitudinal slot between the spaced parallel rails of said guide-means and symmetrical with respect to the longitudinal axis of said slot; and power-means mounted on said base-member constructed and arranged to drive said abrasive wheel.

8. In a mobile skate-sharpening device, the combination including: a base-member provided with a platform having a longitudinal slot therein; skate-blade guide-means comprising spaced-parallel rails secured to the top of said platform

along opposite edges respectively of said slot, skate-blade supporting-rollers mounted between said rails at longitudinally-spaced points therealong to support a skate-blade symmetrically of the longitudinal axis of said slot and resilient skate-blade gripping-fingers secured to said guide-rails intermediate said rollers; handrails fixed to said platform; an abrasive wheel; means to mount said abrasive wheel on said base-member comprising an oscillatable arm and a resilient member cooperatively associated with said arm normally to hold a peripheral portion of said abrasive wheel up in said longitudinal slot between the spaced parallel rails of said guide-means and symmetrical with respect to the longitudinal axis of said slot; power-means mounted on said base-member constructed and arranged to drive said abrasive wheel; and adjusting-means cooperatively associated with said oscillatable arm and said resilient member to limit the upward movement of said abrasive wheel between the spaced parallel rails of said guide-means.

9. A mobile skate-sharpening device comprising: a base-member provided with a platform having a longitudinal slot therein; skate-blade guide-means comprising spaced parallel rails secured to the top of said platform along opposite edges respectively of said slot, skate-blade supporting-rollers mounted between said rails at longitudinally-spaced points therealong and resilient skate-blade gripping-fingers secured to said guide-rails intermediate said rollers; an abrasive wheel; means to mount said abrasive wheel on said base-member comprising an oscillatable arm having a transverse rotatable spindle at the outer free end thereof, said abrasive wheel being mounted on one end of said spindle and a coil-spring arranged to support the free end of said oscillatable arm normally to resiliently hold a peripheral portion of said abrasive wheel up in the said longitudinal slot between the spaced parallel rails of said guide-means; an exhaust fan mounted on the opposite end of said transverse spindle; power-means mounted on said base-member constructed and arranged to drive said spindle, thereby to simultaneously rotate said abrasive wheel and said exhaust fan; adjusting-means cooperatively associated with said oscillatable arm and said coil-spring to limit the upward movement of said abrasive wheel between said spaced parallel guide-rails; and longitudinal guard-plates hinged to the top of said platform in spaced parallel relationship on opposite sides respectively of said longitudinal slot and arranged normally to overlie the upper edges of said guide-rails and said resilient skate-blade gripping-fingers.

10. A mobile skate-sharpening device comprising: a base-member provided with a platform having a longitudinal slot therein; skate-blade guide-means comprising spaced parallel rails secured to the top of said platform along opposite edges respectively of said slots, skate-blade supporting-rollers mounted between said rails at longitudinally-spaced points therealong and resilient skate-blade gripping-fingers secured to said guide-rails intermediate said rollers; an abrasive wheel; means to mount said abrasive wheel on said base-member comprising an oscillatable arm having a transverse rotatable spindle at the outer free end thereof, said abrasive wheel being mounted on one end of said spindle, and a coil-spring arranged to support the free end of said oscillatable arm normally to resiliently hold a peripheral portion of said abrasive wheel up in the said longitudinal slot between the spaced

parallel rails of said guide-means; an exhaust fan mounted on the opposite end of said transverse spindle; power-means mounted on said base-member constructed and arranged to drive said spindle, thereby to simultaneously rotate said abrasive wheel and said exhaust fan; adjusting-means cooperatively associated with said oscillatable arm and said coil-spring to limit the upward movement of said abrasive wheel between said spaced parallel guide-rails; longitudinal guard-plates hinged to the top of said platform in spaced parallel relationship on opposite sides respectively of said longitudinal slot and arranged normally to overlie the upper edges of said guide-rails and said resilient skate-blade gripping-fingers; and latch-means constructed

and arranged to lock and unlock said guard-plate to and from the top of said platform.

EDWIN FRANCIS IVES.
